The ornamental design for an electrical plug body, as shown and described.

DESCRIPTION

FIG. 1 is a perspective view of the instant electrical plug body. The broken line showing of a pair of electrical plug blades is included for the purpose of illustrating environmental structure only and forms no part of the claimed design;

FIG. 2 is a front view thereof;

FIG. 3 is a rear view thereof;

FIG. 4 is a bottom view thereof;

FIG. 5 is a top view thereof;

FIG. 6 is a left side view thereof; and,

FIG. 7 is a right side view thereof.
